UNITED STATES PATENT OFFICE.

WALTER F. STIMPSON, OF DETROIT, MICHIGAN, ASSIGNOR TO THE STIMPSON SCALE & ELECTRIC COMPANY, OF NORTHLAKE, MICHIGAN, A CORPORATION OF MICHIGAN.

SCALE.

1,137,096.

Specification of Letters Patent. Patented Apr. 27, 1915.

Application filed July 9, 1914. Serial No. 849,957.

To all whom it may concern:

Be it known that I, WALTER F. STIMPSON, a citizen of the United States of America, residing at Detroit, in the county of Wayne, 5 and State of Michigan, have invented certain new and useful Improvements in Scales, of which the following is a specification, reference being had therein to the accompanying drawings.

10 The invention relates to scales.

While my improvement may be applied to other types of scales, it is especially designed for scales known as pitless, and consists in the provision of a novel construction of bracket for supporting the fulcrum loop for the platform lever; and further in the peculiar construction and arrangement of the brace members for the platform lever.

20 The invention resides in the novel construction, arrangement and combination of parts as will more fully hereinafter appear.

In the drawings,—Figure 1 is a fragmentary, perspective view of a scale embodying my invention; Fig. 2 is a perspective view of the supporting bracket for the fulcrum loop for the lever; Fig. 3 is a perspective view of the connection between one of the scale levers and the frame; and

30 Fig. 4 illustrates one of the platform levers.

A designates the end sills of the stationary frame; B the cross-connecting members or rods, and C are brackets for supporting the fulcrum loop for the lever. Each of these brackets comprises a body portion D secured to one of the members—preferably the sill—as by bolts E and having a bearing portion F for receiving the rod B. Extending inwardly transverse to the bearing and body portions is an arm G which is arranged in vertical alinement with the end H of the platform lever I, the latter extending transversely of the frame, in the 40 usual manner. The hanger J embraces the arm G and is supported directly thereupon. Preferably the arm G and bearing portion F are provided with strengthening ribs K, the strengthening rib of the arm being arranged upon the upper side thereof and notched to provide a retaining bearing for the hanger. Since the strengthening rib is comparatively narrow, it forms a knife-edge like bearing for the hanger, thereby

permitting the latter to have the desired 55 freedom of movement.

My improved construction of bracket is preferably employed for supporting both the long platform levers I and the short levers L. The long levers are composed of 60 a straight beam a and a brace member b having a flat, central portion d which is secured to a strut e connected to the beam a. The member b has bifurcated portions f inclined upwardly from the free ends of 65 the beam, the bifurcations being arranged upon opposite sides of the straight beam and secured thereto as by means of a bolt g. Preferably the brace is made of two edgewise arranged flat metal strips twisted 70 to form the flattened central portion and connected together at the flattened portion and also at points h i at short distances upon opposite sides thereof. This arrangement provides a very rigid platform lever 75 and effectively prevents sagging of the lever when the scale is subjected to a heavy load.

While I have described the preferred form of my invention, I believe the same subject to various modifications without departing from the scope of the invention and, therefore, do not desire to limit the protection to the exact structure shown.

What I claim as my invention is:—

1. In a scale, the combination of members 85 arranged at substantially right angles, a bracket abutting one of said members, an arm extending from said bracket and inwardly and transversely from said members, a platform lever, and a hanger for the 90 platform lever carried by said arm.

2. In a scale, the combination of members arranged at substantially right angles to each other, a bracket secured to one of said members and having a portion extending 95 transversely therefrom, a strengthening rib for said portion and having a bearing, a platform lever, and a hanger for said platform lever engaging the bearing in said rib.

3. In a scale, the combination of a sill 100 member, a cross-connecting member, a bracket having a body portion attached to one of said members and a portion engaging and alining with the other, and a bearing portion projecting from the body transversely to said members.

4. In a scale, the combination of a sill member, a cross-connecting member, a

bracket secured to one of said members provided with a vertically arranged portion having a knife-edge like bearing extending transversely to said members, a platform lever, and a hanger for said platform lever embracing said transversely extending portion and engaging said bearing.

5. In a scale, the combination of a sill member a cross-connecting member, an arm secured to one of said members extending inwardly and transversely to said members, a bearing for the cross-connecting member extending from the last named member, a platform lever, said arm being in vertical alinement with the end of the platform lever, and a hanger for said end of the platform lever carried by the arm.

6. In a scale, the combination of a sill member, a cross-connecting member, a bracket secured to one of said members and supporting the other, said bracket being provided with a transversely-extending portion having a knife-edge like bearing, a platform lever, and a hanger for said platform lever embracing said transversely-extending portion and engaging said bearing.

7. In a scale, the combination of a sill member, a cross-connecting rod, a bracket having a body portion attached to the sill and having a hollow bearing for receiving the rod, an arm extending inwardly and transversely to the bearing portion, a platform lever having an end thereof arranged in vertical alinement with said arm, and a hanger for the platform lever embracing and carried by the arm.

8. In a scale, a platform lever comprising a substantially straight beam and a brace composed of a flattened central portion and bifurcated extensions secured to the beam on opposite sides thereof and inclining upwardly from opposite ends of said beam, and a strut connecting said flattened central portion of the brace with the beam.

9. In a scale, a platform lever comprising a substantially straight beam and a brace composed of a plurality of flat metal strips arranged edgewise and twisted to form a flattened central portion, a strut connecting said flattened central portion of the brace with the beam, and the ends of the strips upon each side of the flattened central portion being arranged upon opposite sides of and secured to the beam.

10. In a scale, a platform lever comprising a substantially straight beam and a brace composed of two flat metal strips arranged edgewise and twisted to form a flattened central portion, the flattened central portion of the strips being secured together and the strips upon opposite sides of the flattened portion forming bifurcations, means for securing said bifurcations to the beam, and a strut connecting the flattened central portion of the brace with the beam.

In testimony whereof I affix my signature in presence of two witnesses.

WALTER F. STIMPSON.
